FILAMENT LIGHTING CONTACT ASSEMBLY FOR FLUORESCENT LAMP EXHAUST MACHINES

Daniel Mullan, Hillside, N. J., assignor to Westinghouse Electric Corporation, East Pittsburgh, Pa., a corporation of Pennsylvania

Application October 20, 1954, Serial No. 463,430

2 Claims. (Cl. 339—151)

The present invention relates to fluorescent lamp exhaust machines and, more particularly, to a filament lighting contact assembly therefor.

In the exhaust of fluorescent lamps on an automatic fluorescent lamp exhaust machine, the lamp is suspended by its exhaust tubulation (in a downwardly depending position) from a compression rubber assembly of the exhaust head of said machine. It is obvious that when a long tubular fluorescent lamp is held at its upper end at a fixed point, the lower end of said lamp is free to swing, particularly during indexing of the machine, in an unsupported manner. Due to the oscillations of the lower end of the suspended fluorescent lamp undergoing exhaust present contact arrangements (which comprise the yieldingly resilient engagement of the preformed outer portions of the leading-in and supporting conductors with stationary contacts) have proven unsatisfactory. Use of this lower contact assembly produces intermittent and unregulated contact, resulting in unsatisfactory lighting of the lower filament particularly during cathode treatment and resultant inadequate treatment of the lamp while on exhaust. In addition, crooked exhaust tubulations often shift the lower portion of a lamp from the vertical axis and prevent one of the preformed leading-in and supporting conductors of the lower filament mount from engaging the present type lower contact assembly. Vibration of the machine also contributes to faulty contact between the lower conductors and the lower lighting contact assembly.

Hence, it has been found advantageous according to the invention to provide a filament lighting contact assembly, particularly for the lower filament of a fluorescent lamp which is positive in action. The lower filament lighting contact assembly of the invention comprises an insulated reciprocating support plate which carries a contact and a spring biased lever actuating or lever operating pin, a counterweighted lever pivoted above said support plate, engageable with said operating pin and carrying a movable push-down contact finger for securing the preformed leading-in and supporting conductor between the reciprocating lower contact and the tiltable upper contact push-down finger. The support plate is reciprocable on an adjacent guide post by means of cam or pneumatic action.

In its general aspect the present invention has as its objective an improved filament lighting contact assembly for a fluorescent lamp exhaust machine which is positive in action and eliminates faulty contact between the lamp conductors and the contact assembly.

Other objects of the present invention will become apparent to those skilled in the art to which it appertains as the description thereof proceeds both by direct recitation thereof and by implication from the context.

Referring to the drawings in which like numerals of reference indicate similar parts throughout the several views:

Fig. 1 is a diagrammatic plan view of a 48 head fluo-

2

rescent lamp exhaust machine, in which the filament lighting contact assembly of the invention is incorporated.

Fig. 2 is a side elevational sectional view of for example station "29" of the machine of Fig. 1 along the lines II—II of Fig. 3 in the direction of the arrows showing the filament lighting contact assembly of the invention in the closed or filament lighting position.

Fig. 3 is a plan elevational sectional view of stations "27" through "30" of the machine of Fig. 1 along the lines III—III of Fig. 2 in the direction of the arrows, broken away to show details of the filament lighting contact assembly.

Fig. 4 is a fragmentary side elevational view of the filament lighting contact assembly in the open or lamp indexing position.

Referring to the drawings and more particularly to Fig. 1, the reference numeral 10 designates a fluorescent lamp exhaust machine having a rotatable turret 12 provided with a plurality of fluorescent lamp supporting heads 14, for example 48 in the present showing, which are indexable by conventional means (not shown) through a like number of stations. The turret 12 may rotate on the frame (not shown) of the machine 10.

A conventional fluorescent lamp 20, fragmentarily shown in Figs. 2 and 4, has a vitreous envelope 22 sealed at each end to a filamentary mount 24 having a filamentary cathode 26 mounted on leading-in and supporting conductors 28 and 30 thereof. One of the filament mounts 24 is suitably provided with an exhaust tube 32 for insertion into an exhaust head 14, as hereinafter explained.

At either stations "47" or "48" (Fig. 1) the sealed fluorescent lamp 20 may be loaded into an exhaust head 14 of the machine 10. From station "1" through station "42" the lamp 20 may be continuously exhausted. The lamp 20 may be baked at a uniform bulb wall temperature (from top to bottom) of 350° to 400° C. in a suitable oven indicated diagrammatically in Fig. 1. The oven extends from stations "3" through "22" and may be handily provided with oven entrance and exit extensions to help retain the heat.

From station "25" through station "40" the upper and lower cathodes 26 of the fluorescent lamp 20 may be suitably treated by passing a current (by means of an upper lighting contact assembly 38 and a lower lighting contact assembly 40 of the invention respectively) through both cathodes 26, causing the evolution of CO₂ gas, from the emission material. It is necessary to heat the triple carbonate emission material hot enough to insure its complete breakdown into carbon dioxide and the oxides of barium, strontium and calcium. Overheating must be avoided as this will drive active emission material off the cathode and result in short lamp life and envelope end discoloration. Undertreating must also be avoided as this will cause CO₂ to be evolved in the finished lamp, resulting in hard starters, high voltage lamps, discolored ends, and wiggles.

At station "30" the lamp 20 may be dosed with a predetermined amount of distilled mercury by a conventional reactor type doser mechanism (not shown).

The temperature of the envelope 22 at mercury dosing should be above 175° C. When the mercury is added to the hot lamp 20 it is partially vaporized and flushes residual deleterious gases out of the lamp 20 and into a sweep (not shown) extending from the head 14 to a rotary portion of an exhaust valve (not shown). Further, the vaporized mercury provides an ionizable medium for subsequent arcing.

The lamp 20 may be arced from stations "37" through "40." In the lamp arcing positions a high voltage is applied across the lamp 20 (to one leg of each cathode 26 in one position and to the opposite leg on the next

position) and an arc is formed with aid of spark coils placed along (but not in contact with) the lower portion of the lamp 20. The arc further activates the emission coating on the end turns of the cathode 26.

At stations "43" the lamp 20 may be given the proper inert gas fill, suitably argon, at a pressure from 3.0 to 3.6 millimeters of mercury from a suitable inert gas supply (not shown) through the sweep. At station "44" the lamp 20 may be tipped off and either manually or automatically unloaded from the head 14 at either station "45" or "46".

Adjacent the cathode treating stations, namely, stations "25" through "40" a plurality of pairs of lighting contact assembly mounting rods 50 (Figs. 2, 3 and 4) are mounted (radially on either side of a lamp 20) on a frame or stationary portion of the machine 10. These rods 50 carry the upper filament lighting contact assembly 38 and the lower filament lighting contact assembly 40 of the invention. Since only one set of posts 50 is shown in Fig. 3 for four indicated cathode treating stations, namely, stations 27, 28, 29 and 30 it will be understood that a plurality of pairs of posts 50, for example 5, might be employed for the 16 cathode treating stations indicated in the diagrammatic showing of Fig. 1.

Upper filament lighting contact assembly

As shown in Figs. 2 and 3, the upper filament lighting contact assembly 38 comprises an inner and an outer upper lighting contact assembly at each station. Each inner and outer upper contact assembly has a support bracket 52 mounted on one of the posts 50. An arcuate support or plate 54 extends from station "25" to station "40" and is mounted on, and upstanding from, the radially inwardly projecting flanges of the support bracket 52.

An upstanding mounting clamp 56 and a relatively shorter clamp 58 are secured about the support 54, as by bolts 60 at each cathode treating station. As shown particularly in Fig. 2, the clamps 56 and 58 are suitably of insulating material. The upper end of the longer clamp 56 carries an upstanding vertically adjustable contact plate 62, secured to the clamp 56, by suitable bolts which extend through retaining plates 64 and suitable adjustment slots in the contact plate 62.

The contact plate 62, in turn, supports a pair of adjustable and laterally extending contact plate posts or bolts which carry on the inner ends thereof leading-in and supporting conductor contact plates 70. Each of the contact plates 70 has a generally inverted L-shaped configuration. The upper leg portion thereof is inclined upwardly and inwardly toward the vertical axis of a lamp 20 to guide and yieldingly resiliently engage either of the upper leading-in and supporting conductors 28 or 30. Each pair of contact plate posts is connected to a suitable voltage supply by suitable conductors (Fig. 2).

Lower filament lighting contact assembly

Each of the lower filament lighting contact assemblies 40 of the invention (Figs. 2, 3 and 4) comprises an inner and outer lower lighting contact assembly at each cathode treating station. Each inner and outer lower lighting contact assembly comprises a contact finger assembly 78 and a reciprocating lower contact assembly 79.

To provide mounting means for lower filament lighting contact assemblies 40 an upper support bracket 80 is mounted on each of the posts 50 (Fig. 2) suitably below the upper support bracket 52 of the upper filament contact assembly 38 thereabove. An arcuate support or angle 82 is carried on the underside (Fig. 2) of the mounting flange of the support brackets 80. As shown in Fig. 3, a plurality of fulcrum plates 84 of the contact finger assemblies 78, suitably of insulating material, are secured to this arcuate support 82, as by bolts.

A lever yoke 86, having a bifurcated lower end, depends from each of the fulcrum plates 84. A counter-

weighted contact lever 88 is pivotally mounted between the bifurcations of the yoke 86. The lever 88 carries an upper contact finger 90 which is provided with a generally cylindrical leading-in and supporting conductor engaging portion.

Below each of the support brackets 80 a bearing 100 (Figs. 2, 3 and 4) of a lower contact assembly 79 is fixed to a post 50. A lift plate 102 is slidable or vertically reciprocable within each bearing or guide 100. A lower arcuate support or angle 104 similar to the support 82, extends from station "25" to "40" and is affixed to the lift plates 102, as by bolts. An insulating plate 106, similar to fulcrum plate 84, in turn, is mounted on the angle 104 at the cathode treating stations. Each insulating plate 106 carries a lower contact plate 108 of generally the same configuration as the upper contact plate 70 of the upper filament lighting contact assembly 38. A spring centering stud 110 (Figs. 2 and 4) is adjustably threadable into the other end of the insulating plate 106, adjacent the lift plate 102. A compression spring 112, surrounds the stud 110, and carries a lever operating pin 114 thereabove.

The above described lower contact assembly 79 is reciprocable within the bearing 100 on the post 50 by cam action or a pneumatically operated lifting action (not shown). Each pair of lower contacts 108 is connected to a suitable voltage supply by conductors 116 (Figs. 2 and 4).

30

Operation

It will be understood that, as a head 14 of the machine 10 begins to index to the next station, the reciprocable lower contact assemblies 79 of the lower filament lighting contact assembly 40 of the invention are all in their lowermost position on the posts 50, as shown in Fig. 4. Likewise the counterweighted levers 88 of the contact finger assemblies 78 of the lower filament lighting contact assembly 40 are in their uppermost position, thus permitting the lower preformed leading-in and supporting conductors 28 and 30 of a lamp 20 to index between the upper contact fingers 90 and the lower contact plates 108. The leading-in and supporting conductors 28 and 30 are preformed at an angle approximating the angle of the flare of the filament mount 24, thus avoiding kinking and facilitating automatic base threading later in the lamp processing.

During indexing the preformed upper leading-in and supporting conductors 28 and 30 ride off the contact plates 70 of the upper filament lighting contact assembly 38.

At a predetermined time after a head 14 indexes into, say for example station "29," of the machine 10, the lower contact assemblies 79 are reciprocated upwardly on the posts 50 by cam action or pneumatic lifting means (not shown) until the spring biased lever operating pins 114 on the insulating plates 104 engage the counterweighted levers 88. The pins 114 pivot or rotate said levers 88 on the yokes 86 until the lower leading-in and supporting conductors 28 and 30 of lamps 20 are secured between the pivotal contact fingers 90 and the reciprocable lower contact plates 108, thus insuring a positive contact therebetween.

Although a preferred embodiment of the invention has been disclosed it will be understood that modifications may be made within the spirit and scope of the appended claims.

I claim:

1. A lower filament lighting contact assembly for a fluorescent lamp exhaust machine having at least a frame and comprising mounting means adjacent the filament treating stations of said machine, upper contact finger assembly support means on said mounting means, a plurality of upper contact finger assemblies on said upper support means, each of said upper contact finger assemblies comprising an insulating fulcrum plate on said

upper support means, a lever yoke depending from said fulcrum plate, a counterweighted lever pivoted on said yoke and an upper contact finger on said counterweighted lever, lower contact assembly support means reciprocable in said mounting means and a like number of lower contact assemblies on said lower support means, each of said lower contact assemblies being engageable with an upper contact assembly to positively secure therebetween a leading-in and supporting conductor of a fluorescent lamp.

2. A lower filament lighting contact assembly for a fluorescent lamp exhaust machine having at least a frame and comprising mounting means adjacent the filament treating stations of said machine, upper contact finger assembly support means on said mounting means, a plurality of upper contact finger assemblies on said upper

support means, lower contact assembly support means reciprocable in said mounting means and a like number of lower contact assemblies on said lower support means, each of said lower contact assemblies being engageable with an upper contact finger assembly to positively secure therebetween a leading-in and supporting conductor of a fluorescent lamp and comprising an insulating plate on said lower support means, a lower contact plate on said insulating plate and a resilient lever operating pin on said insulating plate for engagement with said upper contact finger assembly.
